UNITED STATES PATENT OFFICE.

WILLIAM N. BERKELEY, OF CEDAR RAPIDS, IOWA.

IMPROVED METHOD OF TURNING BRIDGES.

Specification forming part of Letters Patent No. 55,231, dated June 5, 1866.

To all whom it may concern:

Be it known that I, WILLIAM N. BERKELEY, of Cedar Rapids, in the county of Linn and State of Iowa, have invented a new and useful Improvement in Turning Bridges; and I do hereby declare and make known that the following is a full, clear, and exact description of the same, reference being had to the accompanying drawings, and the letters and figures marked thereon, which form part of this specification.

My said invention relates to that class of bridges for crossing rivers which are so arranged upon a central pier that they may be revolved so as to lie parallel with the stream, forming openings upon each side for vessels to pass through when desired; and it consists in a novel apparatus or arrangement whereby the said bridges are revolved or turned as aforesaid.

To enable those skilled in the art to understand how to construct and use my invention, I will proceed to describe its construction and operation with particularity, making reference in so doing to the aforesaid drawings, in which—

Figure 1 represents a plan or top view of my invention. Fig. 2 is a side view or elevation thereof, and Fig. 3 a central vertical section of the same.

Similar letters of reference in the several figures denote the same parts of my invention.

A represents the pier upon which the revolving pedestal B rests, supporting the bridge C. The said pedestal stands upon a series of balls or conical rollers, (marked 6,) so as to facilitate the revolutions of the bridge as desired.

Upon the top of the said pier, and at a suitable distance from the pedestal B, is arranged a circular track, D, having its outer face V-shaped and its inner face plain, as shown.

Attached to the revolving pedestal B is a horizontal arm, E, which contains the bearings for the vertical shafts F G, which are provided with the cog-wheels J K above said bearings

and with the friction-wheels H I below said bearings, as shown. The shaft F stands up through the bridge, and constitutes the means whereby the power is applied to turn the bridge.

It will be observed that the faces of the said friction-wheels H I lie closely against the appropriate faces of the aforesaid circular track D, being respectively of a corresponding configuration to adapt them thereto. Thus, by revolving the shaft F, the shaft G is revolved by means of the cog-wheels J K, and the friction of said wheels H I upon the circular track D operates to revolve the bridge.

M represents a lever fulcrumed at m upon a suitable support, L, which is attached to the pedestal B, one end thereof being connected with the shaft G in any suitable manner.

N represents another lever, fulcrumed at n in the support L, resting against the shaft F, and being connected with the lever M by the bar O, so that by drawing upon the cord P, which passes beneath a sheave, Q, and thence up to any point desired, the amount of friction between the rollers H I and the bearing D may be increased as may be desired.

The invention herein described may be used for turn-tables also, or for any other analogous purpose.

Having described the construction and operation of my invention, I will proceed to specify what I claim and desire to secure by Letters Patent—

1. In combination with the revolving pedestal, B, the employment of the circular stationary bearing D, the shafts F G, and friction-wheels H I, arranged and operating substantially as and for the purposes specified.

2. In combination with the above, the arrangement of the levers M N and connecting-bar O, as and for the purposes set forth.

WM. N. BERKELEY.
